UNITED STATES PATENT OFFICE.

JAMES E. LITTLE, OF STEELTON, PENNSYLVANIA.

DIGGING AND EXCAVATING MACHINE.

1,095,385.

Specification of Letters Patent.

Patented May 5, 1914.

Application filed November 17, 1910. Serial No. 592,929.

To all whom it may concern:

Be it known that I, JAMES E. LITTLE, citizen of the United States of America, residing at Steelton, county of Dauphin, State 5 of Pennsylvania, United States of America, have invented certain new and useful Improvements in Digging and Excavating Machines; and I do hereby declare the following to be a full, clear, and exact description 10 of the invention, such as will enable others skilled in the art to which it appertains to make and use the same, reference being had to the accompanying drawings, and to letters or figures of reference marked thereon, 15 which form a part of this specification.

My invention relates to digging and excavating machines, more especially to that class of such machines wherein an excavating and elevating shovel or digging bucket 20 is manipulated at a point distant from the place of digging, and to this end it consists of a bucket or shovel provided at its forward end with digging teeth together with means to connect a drag line thereto and at 25 its rear end preferably, but not necessarily, with a gate, the bucket being controlled as to angle of elevation for digging as well as for dumping by means of two lines, one connected to the forward end and the other 30 connected to the rear end thereof.

Heretofore it has been customary to discharge buckets or shovels from the forward or digging end. This has been found to be objectionable for the reason that when digging 35 in clay or a similar sticky material the load does not discharge well for the reason that the digger teeth which are usually quite large prevent a complete discharge of the material and the weight of the material receives 40 no impetus so that it is advisable under such circumstances, to discharge from the rear end. This will enable the material to attain considerable impetus as the discharge takes place usually when the bucket 45 is falling and the material will leave the bucket suddenly with a jerk, which serves to clear the bucket of the sticky material. This feature is absent when a bucket or shovel is emptied by raising the rear end 50 to discharge from the digging end.

In order to fully understand my invention reference will be made to the accompanying drawings in which like parts are similarly designated, and in which—

55 Figure 1 is an elevation of so much of the machinery as is necessary for understanding

the invention. Fig. 2 is a plan view of the frame. Fig. 3 is a side elevation of the bucket or shovel on an enlarged scale. Fig. 4 is a front elevation thereof. Fig. 5 is a modified form of bucket or shovel and Fig. 6 is a front elevation thereof.

In these drawings I have illustrated the bucket as manipulated from a boom but it may just as well be manipulated from a 65 cable-way carriage.

The boom 1 is built up of structural iron and pivoted within a housed platform 2 as is customary. This platform is mounted on rollers 2' so as to be rotatable on a truck 3 provided with wheels 4 adapted to be moved on a temporary track 5. In other words the platform is constructed as a turn table. The boom is provided with a link 6, a pulley 7 and a rope 8 for raising and lowering the 70 boom. This is the customary structure of analogous excavating apparatus and the parts indicated will be well understood by those skilled in the art.

The machinery, Fig. 2, comprises preferably two continuously operating engines 9 for continuously rotating a driving shaft 10. Shaft 10 is provided with a pinion 11 meshing with a gear wheel 12 on a rope drum 13. The shaft 10 is also provided with a pinion 14 meshing with a gear wheel 15 on a rope drum 16, identical with the rope drum 13. The two pinions 11 and 14 are connected to the driving shaft 10 by means of hand-operated clutches 17 and 18. On the 80 driving shaft 10 is also a pinion 19 meshing with a gear wheel 20 capable of being connected to a counter-shaft 21 by means of a clutch 22. This counter-shaft 21 is provided with a pinion 23 meshing with a gear 85 wheel 24 on a rope drum 25. Each of the three drums 13, 16 and 25 is provided with hand-operated band or other brakes 26, 27 and 28 respectively. This mechanism is common to three rope hoists. The forward 90 drum 25 operates the drag rope 29, which is guided over pulley 29^a. The other two drums 13 and 16 operate the bucket manipulating ropes 30 and 31, guided over sheaves 30^a and 31^a respectively at the free end of 95 the boom. The rope 31 is attached in front of the bucket by means of a solid bar or link 32 pivoted to the front end of the rigid yoke 33 extending in front of the bucket, to which the drag rope 29 is also pivotally connected. 100 The other rope 30 is connected to a bail 34 pivoted at or near the rear end of the 105 110

bucket or shovel. The bucket or shovel is provided at its forward or digging end with manganese steel digger teeth 35 and at its rear end, preferably but not necessarily, with shoes 36. The rear or discharge end of the bucket or shovel Fig. 3, is closed by a gate 37 pivoted at 38 to ears 39. The gate 37 carries a sliding latch 40 which holds the gate closed by engagement with a suitable catch below the gate, the latch being automatically drawn out of engagement with the catch, releasing the gate, when the rear end of the bucket swings downward for discharging. The upper edge of the gate 37 carries, preferably, a bell-crank 41 with pivots 42, having one end of the bell-crank connected to the upper end of the latch 40, the other end of the bell-crank being connected by rope 43 to the link 32, which is provided with a number of holes 44, in any one of which the end of the rope 43 may be fastened, so that when the bucket swings on the pivoted connection to the drag rope 29 in, or for discharging, the rope 43 will tighten, as the rear end of the bucket swings into desired position, drawing the latch 40 out of the catch, and allow the gate to swing open. By mounting a suitable guide or pulley on the upper edge of the gate 37 the rope 43 may be connected to the latch 40, securing the same result.

Instead of having a closed bucket or shovel as shown in Fig. 3, this bucket or shovel may be made as indicated in Fig. 5, with a rounded rear end 45 and an open top 46, the other features of construction of this form of bucket being substantially the same as that shown in Fig. 3 with the exception that the link 32 need not be provided with perforations 44 as there is no latch to manipulate.

The operation of the device is as follows:—The drums 13, 16 and 25 may be manipulated independently or simultaneously so that the operator in the inclosed platform 2 can drive any drum at will, brake any drum at will or allow it to run free to pay out its pertaining rope. The inclination of the bucket is controlled by manipulating ropes 30 and 31, so as to hold the bucket at the proper digging angle. The bucket is dragged by rope 29 wound on drum 25. As soon as sufficient material has been dug the bucket is raised by means of ropes 30 and 31 and is pulled toward the platform 2 by means of the drag rope 29 or is allowed to swing out to its limit by paying out the drag rope 29, see dotted line positions Fig. 1. The platform and boom 60 supporting the bucket or shovel is then rotated over the dump cars designed to receive the load or otherwise. Rope 30 is then allowed to pay out and the bucket drops and in so doing the angle between the link 32 and the bucket is increased, thereby produc-

ing a pull on rope 43 which actuates the bell crank 42, withdraws the latch 40, and allows the bottom 47 to swing out. The inertia due to the falling of the rear or gate end of the bucket assists the material to leave the bucket with a jerk and effects a complete discharge. 70

I claim—

1. An excavating and elevating shovel having a latch gate at its rear end, and means for dragging said shovel forward for filling the same; in combination with a pair of independently and simultaneously operable ropes for maintaining the shovel at any incline to regulate the depth of excavation, for raising the shovel and for sustaining the load, one of said ropes constituting means for tripping the shovel to discharge from its rear end when raised independently of the other, and means operated by the tipping rope to operate the latch for opening the gate. 75

2. The combination with an excavating and elevating shovel having a latch gate at its rear end and means for dragging the shovel forward for filling the same; of a plurality of depending ropes for maintaining the shovel at any incline to regulate the depth of excavation, and simultaneously acting to raise the shovel, one of said ropes connected forward of the digging end of the shovel acting to tip the shovel, to discharge from its rear end, and means actuated by the tipping rope to operate the latch for releasing the gate. 90

3. In an excavating apparatus, the combination with an excavating and elevating shovel and means for dragging said shovel connected in front of its forward end for filling the same; of two ropes, one of which is connected to the shovel in front of its forward end and the other to the shovel near its rearward end, a rear end gate for the shovel, a latch controlling the same, said latch operated from the rope connected in front of the forward end of the shovel and operated when the rear end of the shovel is dropped. 95

4. In an excavating apparatus, the combination with an excavating shovel and means connected in front of the forward end of the shovel for dragging the same; of two ropes, a link pivoted in front of the forward end of the shovel to which one of said ropes is connected, means near the rear end of the shovel to which the other rope is connected, a hinged gate for closing the rear end of the shovel, a latch to hold the gate closed, a bell-crank carried on the gate one arm of which is connected to the latch and means to connect the other arm of the bell crank to the link. 110

5. In an excavating apparatus, the combination with an excavating shovel, a drag rope connected in front of its forward end, 115

a rear hinged gate and a latch for said gate; of a supporting rope connected to the shovel between its center of gravity and said gate, a link connected to the drag rope pivot in 5 front of the shovel, a second supporting rope connected to the link, and latch-operating means connected to the link.

6. In an excavating apparatus, the combination with an excavating shovel, a drag 10 rope connected to its forward digging end, a rear hinged gate and a latch for said gate; of a bail pivoted to the shovel between its center of gravity and said gate, a rope attached to the bail to assist the supporting

and lifting thereof, a link pivoted to the forward end of the shovel, a second rope connected to the link, latch operating means connected to the link and means on the link to vary the extent of movement of the latch operating means. 15

In testimony that I claim the foregoing as my invention, I have signed my name in presence of two subscribing witnesses. 20

JAMES E. LITTLE.
